UNITED STATES PATENT OFFICE.

CHARLES F. WILLINGHAM, OF HOUSTON, TEXAS.

TIE-CLASP.

1,113,271.

Specification of Letters Patent.

Patented Oct. 13, 1914.

Application filed January 12, 1912. Serial No. 670,765.

To all whom it may concern:

Be it known that I, CHARLES F. WILLINGHAM, a citizen of the United States, residing at Houston, in the county of Harris and State of Texas, have invented certain new and useful Improvements in Tie-Clasps, of which the following is a specification.

My invention relates to new and useful improvements in tie clasps.

10 The object of the invention is to provide a device of the character described, which may be secured to the ordinary neck tie, commonly worn by men and which will hold said tie firmly in position and prevent the 15 same from becoming loose or untied.

With the above and other objects in view, the invention has particular relation to certain novel features of construction and arrangement of parts, an example of which 20 is given in this specification and illustrated in the accompanying drawings, wherein—

Figure 1 is a front view of the clasp. Fig. 2 is a rear view thereof, and Fig. 3 is a sectional side elevation thereof. Fig. 4 is an 25 enlarged fragmentary view showing the hinge connecting the clasp and the hasp.

This device includes a surrounding clasp 1 which is designed to be secured around the knot of the tie and rest closely against the 30 collar of the wearer in front. This clasp is slightly funnel shaped and the front portion thereof is open so as to expose the tie to view, having only the stays 2 and 3, running from top to bottom and from side to side,

35 respectively, thereof. The rear portion 4 of the clasp is hinged to the clasp 1 so that it may be opened and closed in the manner of a hasp. This portion 4 swings on the hinges 5, and connected to one of said 40 hinges 5, at one end and to the clasp 1 at the other, is the coil spring 6, which is so arranged that its tension against the hinge 5 normally tends to hold the hasp 4 open. The free side of the hasp 4 is provided with

45 an eye 7 and the corresponding edge of the clasp 1 is provided with two similar eyes 8 and 9, through which the rod 10 is arranged to slide back and forth. Surrounding this rod 10 is a coil spring 11, one end 50 of which rests against the eye 9 and the other end of which is secured on the rod 10 by means of collar 10' and the tension of this spring tends to hold said rod in position in said eyes 8 and 9 so that the free 55 end thereof will project beyond the eye 8 and engage in the eye 7 of the hasp 4 when

the same is closed. The rod 10 has a suitable head 12 which engages against the eye 9 and limits the projection of the free end of said rod 10 through the eye 8. When it is 60 desired to open the hasp 4, the rod 10 may be forced back manually, overcoming the tension of spring 11 until the free end thereof is withdrawn into the eye 8 and disengaged from the eye 7 of the hasp 4, when 65 the operation of the spring 6 will force said hasp open and the device may then be readily applied to the tie.

The numeral 13 refers to a spring stay, which is secured to the lower end of hasp 70 4 by means of a rivet 14 and the upper end of which is free and has an inward curve, so as to engage against the rear side of the tie and hold the same clasped firmly between said stay and the clasp 1. This stay has an 75 oblong slot 15 which registers with a similar slot 16 in the hasp 4 and passing through these slots is a sliding rivet 17, having an enlarged head at each end so as to prevent the disengagement of the same from said 80 slots. As this rivet 17 is moved up or down, the free end of stay 13 is forced outwardly from the tie or springs inwardly against it as is indicated in full and dotted lines in Fig. 3. The lower end of hasp 4 carries an 85 inwardly extending tongue 18 which projects against the tie from behind and holds the same firmly against the lower portion of the clasp 1 and thus gives a better form thereto.

90 What I claim is:—

1. A device of the character described composed of a suitable clasp and a hasp hinged thereto in the rear thereof, a latch for locking said hasp in a closed position, 95 a stationary stay having one end free secured to said hasp at its lower end on the inside, a sliding rivet engaging with said hasp and stay and regulating the free end of said stay relative to the hasp.

100 2. A device of the character described composed of a suitable clasp and a hasp hinged thereto on its rear side, a resilient member connected with said clasp and hasp, and tending to normally hold said hasp open, a latch for locking said hasp closed, a resilient stay secured to the inside of said hasp at its lower end and having its upper end free and a means having slid able engagement with said hasp and stay whereby 110 the free end of the stay may be regulated relative to the hasp.

3. A device of the character described composed of a surrounding clasp and a hasp hinged thereto at one side, a resilient member engaging with said clasp and hasp tending 5 to hold the hasp open, a latch carried by the clasp and arranged to engage with the hasp when the same is closed and lock the same closed, a resilient member normally tending to hold said latch in engagement with said 10 hasp, a resilient stay rigidly secured at its lower end to the inside of the hasp and having one end free and means having slidable engagement with the stay and hasp whereby the position of the free end of the stay may 15 be regulated relative to the hasp.
4. In a device of the character described, a surrounding clasp and a hasp hinged

thereto on its rear side, said hasp having a lengthwise slot therein, a coil spring engaging with said clasp and hasp and tending 20 to hold the hasp open, a latch carried by the clasp comprising a plurality of eyes and a pin adapted to pass therethrough and arranged to engage with the hasp and pass through an eye carried by said hasp when 25 the same is closed and lock the same in a closed position.

In testimony whereof I have signed my name to this specification in the presence of two subscribing witnesses.

CHARLES F. WILLINGHAM.
